US0D1095100S

(12) **United States Design Patent** (10) **Patent No.:** **US D1,095,100 S**
(45) **Date of Patent:** **** Sep. 30, 2025**

(54) **COLLECTABLE CARD DISPLAY HOLDER**

(71) Applicant: **Jeffrey Parker**, Bloomington, IN (US)

(72) Inventor: **Jeffrey Parker**, Bloomington, IN (US)

(73) Assignee: **A.C.E. Brands, LLC.**, Bloomington, IN (US)

(**) Term: **15 Years**

(21) Appl. No.: **29/862,021**

(22) Filed: **Dec. 6, 2022**

(51) **LOC (15) Cl.** **19-02**

(52) **U.S. Cl.**

USPC **D19/91; D20/43**

(58) **Field of Classification Search**

USPC D6/366, 449, 512, 553, 567, 573, 657;

D19/75, 78, 86, 91, 135; D21/392;

D20/43; D14/253

CPC A47F 7/14; A47F 7/143; A63F 1/10; B42F

17/02

(57) **CLAIM**

The ornamental design for a collectable card display holder as shown and described.

DESCRIPTION

FIG. 1 is a front view of one embodiment;

FIG. 2 is a right view;

FIG. 3 is a left view;

FIG. 4 is a top view;

FIG. 5 is a bottom view;

FIG. 6 is a rear view;

FIG. 7 is a top right perspective view;

FIG. 8 is a right perspective view;

FIG. 9 is a front view of another embodiment;

FIG. 10 is a right view;

FIG. 11 is a left view;

FIG. 12 is a top view;

FIG. 13 is a bottom view;

FIG. 14 is a rear view; and,

FIG. 15 is a top right perspective view.

The long dash/short dash broken lines in FIG. 8 illustrate environmental structure that form no part of the claimed design. The evenly dashed broken lines illustrate portions of the collectable card display holder that form no part of the claimed design.

1 Claim, 5 Drawing Sheets
